UNITED STATES PATENT OFFICE.

JOHN T. BIERDS, OF BROOKLYN, NEW YORK.

MACHINE FOR BORING AND GROOVING SASH-STILES.

SPECIFICATION forming part of Letters Patent No. 289,497, dated December 4, 1883.

Application filed September 26, 1883. (No model.)

To all whom it may concern:

Be it known that I, JOHN T. BIERDS, a citizen of the United States, and a resident of Brooklyn, in the county of Kings and State of New York, have invented certain new and useful Improvements in Machines for Boring and Grooving Sash-Stiles, of which the following is a specification.

The object of my invention is to provide an improved means whereby the boring and grooving of window-sash stiles for the attachment to the same of the sash-weight cords may be accomplished accurately and with much more rapidity than heretofore.

15 The invention consists in the construction and combination of the various parts, as will be hereinafter described and claimed.

In the accompanying drawings, Figure 1 represents a vertical section of a sash-stile boring and grooving machine embodying my invention, the section being taken on the line $x-x$ of Fig. 2. Fig. 2 is a plan view of the same. Fig. 3 is a partial section taken on the line $y-y$ of Fig. 2, and showing the grooving-saw. Fig. 4 is a section of the grooved and bored portion of a stile, and showing in dotted lines the position of the drill and drill-guide while boring the horizontal hole through which the cord is inserted. Fig. 5 is a side view of a 25 portion of the stile completed; and Fig. 6, a longitudinal section of the same, taken on the line $z-z$ of Fig. 5.

A is the frame of the machine. B is a counter-shaft mounted in suitable bearings on the 35 frame A, and receiving its motion, by means of belt a and pulley b , from a main shaft arranged somewhere in the building where the machine is placed. The drill-shaft is arranged on top of the frame at right angles to the 40 shaft B, and receives its motion from the said shaft by means of a pulley, b' , and a quarter-turned belt, b^2 , which latter runs up over and around a pulley, c , upon the drill-shaft C.

The shaft D of the ordinary wobble-saw, d , 45 by which the groove in the sash-stile is cut, is mounted in bearings underneath the top of the frame A and parallel with the shaft B, from which latter it receives its motion by means of a belt, b^4 , which runs over pulleys b^3 and d' , 50 secured on the shafts B and D, respectively. The saw d is one of the ordinary wobble-saws

set at a slight inclination to the axle, so that, in revolving, it will cut a wider space than its own thickness. In order to regulate the depth of the cut by which the groove in the stile is 55 made, a separate feed-board, d^2 , is hinged to the top of the frame, as shown in Figs. 2 and 3, and a set-screw, d^3 , passing through the top or table from the underside thereof, serves wherewith to regulate the inclination or height 60 of the feed-board d^2 , and consequently the depth at which the saw will cut into the stile, the latter being held down upon the feed-board d^2 while the groove is being cut. At the side 65 of the saw d a guide-board, d^4 , is attached to 70 and adjustable upon the feed-board, to regulate the distance of the groove from the edge of the stile, the latter being placed simultaneously against the board d^2 and guide d^4 while the saw is operating upon it. In boring and 75 grooving the stile E, (see Figs. 4, 5, and 6,) the sockets e and e' are first bored, then the groove e^2 is cut, and finally the hole e^3 between the sockets is bored, through which the sash-weight cord is inserted, as in Fig. 6, and a 80 knot tied on its end to prevent it from slipping out.

F is the drill by which the sockets e e' are bored, and G the drill by which the hole e^3 is bored. These drills are attached to opposite ends of the same drill-shaft, C, (which latter is revolving in suitable bearings, c' , on the top of the frame A,) both ends of the shaft C being socketed to receive the drill-heads, and being threaded on the outside, slightly cone-shaped and split, and provided with tightening-nuts c^2 for the purpose of holding the drills, in the same manner as is usual in drill-chucks. In boring the sockets, the stile is placed upon the table f and pushed up against cleats or 85 stops f' , by which the depth of the socket is regulated. The drill G, by which the hole e^3 is bored, being necessarily very long, (as it has to reach through the full length of the groove e^2 , and, in addition thereto, the distance 90 between the two sockets,) the manner in which I have mounted and guided the drill is the most important feature in this construction. Heretofore the holes e^3 have always 95 been bored by hand, which is not only tedious and liable to get the hole not always in the same position, but also liable to the difficulty 100

that the drill springs owing to its great length, which increases the labor of boring. To overcome this difficulty I support the drill along the whole length of the groove e^2 and socket e 5 by means of a block, g , having, at intervals, bearings g' , in which the shank of the drill revolves, and by which the drill consequently is centered, so that the hole bored will always be in the same position. This block and bearing $g' g$ is of the right size to fit in the groove e^2 , in the manner indicated in dotted lines in Fig. 4. In boring the hole e^3 , the stile is entered between three gage-blocks or guides, H H I, the two gage-blocks H being arranged one at either side of the stile, and adjustable and securable in position by means of slides h and set-screws h' , and the gage-block I being arranged above the stile and adjustable by means of slots i and bolts i' between two 15 brackets, J, arranged one on each side of the block I, as shown in Figs. 1 and 2. The boards H H I are made adjustable for the purpose of adapting them to act as guides for stiles of different sizes.

25 K is a leaf hinged to the front edge of the top of the frame A, so that it may be swung down when not in use, and is supported, when in use, by means of a brace, L, hinged to one of the cross-bars between the frame-legs, and 30 stopping with its upper end against a cleat, l, underneath the leaf K, as shown in Fig. 1. When a stile E is being operated upon by the drill G, its outer and main portion is resting upon the said leaf K, which latter, for 35 this purpose, should be so hinged as to be flush with the surface which receives the inner end of the stile, as shown in Fig. 1.

In using the machine, the stile is first placed

on the table f and the sockets $e' e'$ bored by means of the drill F. It is then placed upon 40 the feed-board d^2 and the groove e^2 cut by the wabble-saw d , and, finally, the hole e^3 is bored by the guided drill G, as aforesaid.

Having thus described my invention, I claim as new and desire to secure by Letters Patent— 45

1. In a stile-boring device, a drill, G, having one or more bearings, g' , along its shank, the said bearings being adapted to enter the groove e^2 of a sash-stile when boring the hole e^3 for insertion of the sash-cord, substantially 50 as set forth.

2. The combination of the drill G, revolving in bearings g' within the groove e^2 of the stile, with the adjustable side guides, H H, and top guide, I, substantially as hereinbefore set 55 forth.

3. The drill-shaft C, having a chuck at either end, in combination with the socket-drill F and cord-hole drill G, the latter being centered in bearings g' , substantially as and 60 for the purpose set forth.

4. A sash-stile machine having the socket-drill F and cord-hole drill G arranged upon the same axle, and the groove-cutter d arranged at the side thereof, for the purpose of 65 accomplishing the grooving, socketing, and boring in the same machine, as specified.

In testimony that I claim the foregoing as my invention I have signed my name, in the presence of two witnesses, this 17th day of 70 September, 1883.

JOHN T. BIERDS.
